UNITED STATES PATENT OFFICE.

CALEB E. SUMMERS, OF DAYTON, OHIO, ASSIGNOR TO GENERAL MOTORS RESEARCH CORPORATION, OF DAYTON, OHIO, A CORPORATION OF DELAWARE.

COMPENSATING ROCKER ARM SUPPORT.

Application filed October 30, 1923. Serial No. 671,687.

To all whom it may concern:

Be it known that I, CALEB E. SUMMERS, a citizen of the United States of America, residing at Dayton, county of Montgomery, 5 State of Ohio, have invented certain new and useful Improvements in Compensating Rocker Arm Supports, of which the following is a full, clear, and exact description.

This invention relates to internal combustion engines including valve mechanism of the overhead type, that is, the valves are operated by means of rocker arms mounted above the cylinder and by push rods extending along the cylinder and into the crank 10 case.

One of the objects of the present invention is to compensate for changes in temperature to which the valve mechanism is subjected in order that throughout the range 20 of engine operating temperatures the clearance between the rocker arm and cooperating parts will be maintained practically constant. In order to accomplish this object, one form of the invention consists in sub- 25 jecting the push rod to the heated air surrounding the engine cylinder and in using a push rod which is substantially longer than the engine cylinder in order that the total expansion of the push rod will be substantially 30 the same as the total expansion of the cylinder. The push rod extends a distance above 35 the cylinder head and operates a rocker arm which is pivoted above the cylinder head upon a support which is mounted upon the cylinder head. The invention provides 40 means for cooling this support for the rocker arm so as to minimize the elongation of this support due to the increase in engine temperature when in operation.

Other further objects and advantages of the present invention will be apparent from the following description, reference being had to the accompanying drawings, wherein 45 a preferred embodiment of one form of the present invention is clearly shown.

In the drawings:

Fig. 1 is an end view of an engine partly in section which includes a form of the present invention.

Fig. 2 is a fragmentary plan view of the engine shown in Fig. 1.

Fig. 3 is a fragmentary sectional view showing a modified form of the invention.

In the drawings, 20 indicates the crank- 55 case of an internal combustion engine sup-

porting one or more cylinder 21 provided with cooling ribs or fins 22. One form of such cylinder is disclosed in the copending application of C. F. Kettering, Serial No. 514,014, filed November 9, 1921. To the 60 head end of cylinder 21 there is attached superstructure 23 which provides an intake passage 24 and an exhaust passage 25, and guides for the stems 26 of the engines valves, one of which is indicated in dotted lines in 65 Fig. 1. As shown in Fig. 2 there is one superstructure 23 for each pair of cylinders. Superstructure 23 is thermally insulated from the head of the cylinder 21 by means of a nonconducting gasket 27.

A portion of the fins 22 of each cylinder is surrounded by a draft tube 28 which merges into an air manifold 29 closed at one end and having the other end open and communicating with an engine operated air 70 circulating fan 30 which is driven by the engine by means of pulleys 31 and 32 and a belt 33. When the fan operates, air is caused to circulate upwardly through the heat dissipating fins 22 to carry away 75 heat by the fins from the cylinder walls. The heated air passing upwardly through the several draft tubes 28 is conducted 80 through the air manifold 29 to the fan 30 which expels the air between its fan blades 85 34.

The valves of the engine are operated by 90 mechanism which includes in each case a cam 40 located on cam shaft 41 operated by the engine, a push rod 42 operated by cam 40 and a rocker arm 43 which is mounted 95 on a rocker arm shaft 44. The shaft 44 is supported above the engine cylinder by means which is not subjected to the amount 100 of temperature change during engine operation to which such parts as the engine cylinder and push rods are subjected. This means for supporting the rocker shaft 44 includes a tubular pedestal 50 which is attached to the superstructure 23 by means of 105 a stud 51 attached thereto and by means of a nut 52 threaded on the upper end of stud 51. A non-conducting washer 58 assists in thermally insulating the pedestal 50 from part 23. A spring washer 59 is located between the nut 52 and pedestal 50. The stud 51 extends through the tubular passage 53 provided within the pedestal 50 and is received by a notch provided in the rocker 110 shaft 44 to prevent said shaft from turning.

in the apertured shaft supporting portion 54 with which the pedestal 50 is provided. The passage 53 is provided with outlets at 55 and 56 and with an inlet pipe 57 which 5 extends through the air manifold 29 and outside the draft tube 28.

Rotation of the cam shaft 41 produces reciprocation of the push rod 42, oscillation of rocker arm 43 and reciprocation of the 10 engine valve 26. The drawings show a conventional valve return spring 60 which yieldingly maintains the valve on its seat and the lower end of the push rod in engagement with the cam 40.

15 The clearance between the rocker arm 43 and the valve is adjusted at the ball and socket joint 61, 62 in the usual manner by adjusting the screw 63 and locking the screw in position by a lock nut 64. This adjustment of clearance is usually made when the 20 engine is cold. Since the engine cylinder is heated during engine operation to a higher temperature than the push rod 42, the cylinder tends to expand faster than the push 25 rod.

In order that the valve clearance be maintained constant throughout the range of engine temperature increase, it is desirable that the total expansion of the push rod should 30 be substantially equal the total expansion of the cylinder and that the total expansion of the pedestal 50 be negligible. The push rod 42 is therefore located in the path of air which circulates over the engine fins. Certain of the fins such as fins 22^a in Fig. 2 are shorter radially than other fins so that the push rod may be located relatively closer to the fins and to the engine cylinder wall. In this way the push rod is subjected to the 40 heat dissipated from the cylinder wall by means of the cooling fins and circulating air. While the temperature of the push rod 42 may not be as great as the temperature of the hottest part of the cylinder walls yet the temperature of the push rod will be substantially increased during engine operation. By making the push rod substantially longer than the engine cylinder and by making it of material having the desired coefficient of 45 expansion the total endwise expansion of the push rod can be made substantially the same as the total lengthwise expansion of the cylinder.

50 The interior of the pedestal 50 is in direct communication with air outside of the draft tube 28 and the air manifold 29 so that the operation of the fan 34 causes relatively cool air to enter the pedestal 50 through passage 57 and to be drawn out through passages 55 and 56. In this manner the temperature of the pedestal 50 is maintained substantially below that of the engine cylinder and superstructure. The nonconducting washer 58 located between the pedestal 50 and the 55 superstructure 23 tends to prevent heat

transfer directly from the superstructure. The stud 51 may become hotter than the pedestal 50 and therefore expand lengthwise to a greater degree. Expansion of the stud 51 may take place without effecting 70 expansion of the pedestal 50 because the stud is permitted to move upwardly relative to the rocker arm shaft 44. This expansion of the stud 51 will tend to lift the nut 52 but pressure between the nut 52 and the upper end of the pedestal 50 is maintained 75 through the spring washer 59.

By maintaining the pedestal 50 relatively cool the endwise expansion thereof can be rendered substantially negligible. Consequently, the vertical distance between the superstructure 23 and the rocker shaft 44 changes but a slight amount. Since means have been provided to maintain a pedestal 80 of substantial length relatively cool, the greater length of the push rod as compared with the engine cylinder can be taken advantage of in the matter of compensating 85 for changes in temperature, although the engine cylinder may be heated to a greater 90 degree than the push rod.

A modified form of the invention is shown in Fig. 3. A tubular pedestal 70 is employed having an inlet pipe 71 leading into a central passage 72 connected with outlets 95 73 and 74. The pedestal 70 supports the rocker shaft 44 centrally of the passage 72; and the stud 51 extends through a hole provided in the shaft 44. The pedestal 70 is maintained cool by air entering the passage 100 71 and leaving through the passages 73 and 74.

While the form of embodiment of the invention as herein disclosed, constitutes a preferred form it is to be understood that 105 other forms might be adopted, all coming within the scope of the claims which follow.

What is claimed is as follows:

1. An engine comprising, in combination, 110 a cylinder, a valve seated adjacent the cylinder head, a rocker arm mounted for operating the valve, means for supporting the rocker arm at a substantial distance from the cylinder head, a push rod for operating the rocker arm, means for subjecting the push rod to heat developed by the engine, and means for maintaining the temperature of the rocker arm support below that of the push rod during engine operation.

2. An engine comprising, in combination, 115 a cylinder, a valve seated upon the cylinder head, a rocker arm support extending from the cylinder head, a rocker arm supported thereby for operating said valve, a push rod substantially longer than the cylinder extending lengthwise thereof, means for circulating a fluid around the cylinder to cool the same and to heat the push rod, and means for maintaining the rocker arm sup- 120 125 130

port at a temperature lower than that of the push rod during engine operation.

3. An engine comprising, in combination, a cylinder provided with cooling fins, a valve seated upon the cylinder head, a rocker arm support extending from the cylinder head, a rocker arm supported thereby for operating said valve, a push rod substantially longer than the cylinder extending lengthwise thereof, and adjacent the fins, means for circulating air about the fins and push rod to cool the cylinder and heat the push rod, and means for subjecting the rocker arm support to air which is cooler than the air heated by engine operation.

4. An engine comprising, in combination, a cylinder provided with cooling fins, a valve seated upon the cylinder head, a rocker arm support extending from the cylinder head, a rocker arm supported thereby for operating said valve, a push rod substantially longer than the cylinder extending length-

wise thereof, and adjacent the fins, means for circulating air about the fins and push rod to cool the cylinder and heat the push rod, and means for subjecting the rocker arm support to air which is cooler than the air heated by engine operation.

5. An engine comprising, in combination, a cylinder provided with cooling fins, a valve seated upon the cylinder head, a rocker arm support extending from the cylinder head, a rocker arm supported thereby for operating said valve, a push rod substantially longer than the cylinder extending lengthwise thereof, and adjacent the fins, an air duct enclosing a portion of the push rod and fins, suction fan communicating with the air duct, and a duct communicating with the fan for subjecting the rocker arm support to air which is cooler than the air heated by the engine.

In testimony whereof I hereto affix my signature.

CALEB E. SUMMERS.
